UNITED STATES PATENT OFFICE

EDMUND W. BRADY, OF NEW BRITAIN, CONNECTICUT, ASSIGNOR TO THE BRADY ELECTRIC & MANUFACTURING COMPANY, OF NEW BRITAIN, CONNECTICUT

LAMP LEAD BRACKET

Application filed January 20, 1931. Serial No. 509,939.

My invention relates to a lamp lead bracket and more especially to a bracket provided with a split insulator, the parts of which may be readily separated to facilitate the introduction of a wire or wires therebetween.

The invention, generally speaking, relates to that type of insulator and insulator support shown and described in the patent to Herbert O. Rockwell, No. 1,505,730, August 19, 1924, in which a generally hollow cylindrical insulator is shown divided along its axis into semi-cylindrical parts mounted between a pair of hinged straps which may be opened to permit the separation of the insulator parts during the insertion of the wire or wires, and then clamped together to secure and hold the wires in place.

Ordinarily, the parts of the insulator have been loosely mounted in the straps and readily become separated therefrom when the straps are opened. One of the objects of the present invention is to bring about a form of lamp lead bracket in which the parts of the insulator are attached to the straps so that the latter may be separated without any danger of the insulator parts separating from the bracket and dropping to the ground or otherwise inconveniencing a lineman.

A further object of the invention is to bring about a form of lamp lead bracket in which broken insulator parts may be readily detached from the straps or other supporting members and replaced by new parts.

To these and other ends, the invention consists in the novel features and combinations of parts to be hereinafter described and claimed.

In the drawing:

Fig. 1 is a side elevational view of a lamp lead bracket according to my invention;

Fig. 2 is an end view of the same but on an enlarged scale;

Fig. 3 is a cross-sectional view taken along line 3-3 of Fig. 2;

Fig. 4 is a view showing the bracket in position for insertion or removal of the insulator parts, and

Fig. 5 is a cross-sectional view along line 5-5 of Fig. 1.

Referring now to the drawing in which I

have illustrated my invention by showing a preferred embodiment of the same, the reference numeral 10 indicates in general the improved lamp lead bracket which includes a pair of straps 11 and 12, generally semi-circular in shape and each having at one of its ends a loop designated herein by the reference numerals 13 and 14, a cylindrical opening 15 being formed in loops 13 and 14 in which a hinge pin 16 is mounted. At the opposite ends of straps 11 and 12 from loops 13 and 14 are arms 17 and 18, through which a bolt 19 passes, bolt 19 urging the straps 11 and 12 towards one another to clamp therebetween an insulator, generally designated by the reference numeral 20. Insulator 20 comprises two separable semi-cylindrical parts 21 and 22, grooved at 23 and 24 to form, when the parts are assembled together, an axially directed wire receiving opening 25.

Insulator parts 21 and 22 are provided at their ends with flanges 26, which are apertured as at 27 for the reception of flexible bars or rods 28, spaced radially except at their ends, a sufficient distance from the insulator parts 21 or 22 to permit the reception of the straps 11 and 12 therebetween. The straps 11 and 12 may be supported in any convenient manner, herein a pin 29 being provided for this purpose which is riveted in the strap 11 at 30 and provided at its opposite end with threads 31 for reception in a telegraph pole or other support.

In assembling the insulator parts 21 and 22 on the straps 11 and 12, the arms 17 and 18, as the case may be, are inserted between the rod 28 and the body of the respective insulator, as shown in the left-hand end of Fig. 4, whereupon the insulator may be moved along the strap into the position shown in the right-hand end of Fig. 4, and then rotated into final position on the strap. In case either or both of the insulator parts become broken they may be readily removed by reversing the assembling operation and new parts substituted therefor.

It will be readily understood from the above description of the invention that I have provided a lamp lead bracket or the like, in

which the insulator may be readily opened up to permit the introduction of a wire or wires without there being any danger of the insulator parts becoming detached from their supports. Furthermore, in case either or both parts of the insulator become broken they may be readily replaced by a lineman without detaching the insulator support from its supporting structure.

10 While I have shown and described a preferred embodiment of my invention it will be understood that it is not to be limited to the details shown, but is capable of modification and variation within the spirit of the 15 invention and the scope of the appended claims.

What I claim is:

1. In a lamp lead bracket, a generally cylindrical insulator having an axially directed aperture, said insulator being divided axially into semi-cylindrical parts, a pair of semi-circular strap members each embracing one of said insulator parts, means for clamping the straps together with the insulator parts therebetween, and means on said insulator parts embracing said straps to detachably secure the insulator parts on the straps, said last named means comprising relatively narrow bars, the ends of the bars being attached to the insulator parts, and the intermediate parts of the bars being spaced from the insulator parts a sufficient distance to permit the ready introduction and withdrawal of the straps between the bars and insulator parts.

2. In a lamp lead bracket, a generally cylindrical insulator having annular flanges at its ends and an axially directed aperture, said insulator being divided axially into semi-cylindrical parts, a pair of semi-circular strap members mounted one on each of the insulator parts between the flanges thereon, said straps being hingedly connected together at one end, means for clamping the other ends of the straps together, and means for detachably securing the straps on the insulator parts comprising axially directed bars having their ends mounted on said insulator parts and being spaced between their ends a sufficient distance from the insulator parts to permit the free insertion and withdrawal of the straps thereunder.

3. In a lamp lead bracket, a generally cylindrical insulator having annular flanges at its ends and an axially directed aperture, said insulator being divided axially into semi-cylindrical parts, a pair of semi-circular strap members mounted one on each of the insulator parts between the flanges thereon, said straps being hingedly connected together at one end, means for clamping the other ends of the straps together, and means for detachably securing the straps on the insulator parts comprising axially directed relatively nar-

row bars mounted in said flanges and spaced from the insulator parts a sufficient distance to permit the insertion and withdrawal of the straps between the bars and insulator parts.

4. In a lamp lead bracket, a generally cylindrical insulator having annular flanges at its ends and an axially directed aperture, said insulator being divided axially into semi-cylindrical parts, a pair of semi-circular strap members mounted one on each of the insulator parts between the flanges thereon, said straps being hingedly connected together at one end, means for clamping the other ends of the straps together, and means for detachably securing the straps on the insulator parts comprising axially directed bars having their ends mounted on said insulator parts, said straps being slidably received between said bars and insulator parts.

5. In a lamp lead bracket, a generally cylindrical insulator having annular flanges at its ends and an axially directed aperture, said insulator being divided axially into semi-cylindrical parts, a pair of semi-circular strap members mounted one on each insulator part, said straps embracing the parts between the flanges thereon, means for clamping the straps together with the insulator parts therebetween, and means on said insulator parts extending between said flanges and forming in conjunction therewith apertures through which the straps may be threaded for detachably securing the straps on the insulator parts.

In witness whereof, I have hereunto set my hand this 16 day of January, 1931.

EDMUND W. BRADY.
